(57) **CLAIM**

The ornamental design for a link chain, as shown and described.

DESCRIPTION

FIG. 1 is a side perspective view of a link chain showing my new design, the opposite side perspective view being a mirror image thereof;

FIG. 2 is a top view of a link chain showing my new design, the opposite side view being a mirror image thereof;

FIG. 3 is a side view of a link chain showing my new design, the opposite side view being a mirror image thereof;

FIG. 4 is a perspective view of a segment of the link chain in FIG. 1, shown separately for clarity of illustration;

FIG. 5 is a side elevational view of a first type of link of the link chain in FIG. 1, shown separately for clarity of illustration, the opposite side view being a mirror image thereof;

FIG. 6 is a top plan view of the first type of link of FIG. 5, the bottom plan view being a mirror image thereof;

FIG. 7 is a perspective view of the first type of link of FIG. 5;

FIG. 8 is a side elevation view of a second type of link of the link chain in FIG. 1, shown separately for clarity of illustration, the opposite side view being a mirror image thereof;

FIG. 9 is a top plan view of the second type of link of FIG. 8, the bottom plan view being a mirror image thereof; and, FIG. 10 is a perspective view of the second type of link of FIG. 8.
